UNITED STATES PATENT OFFICE.

LOUIS G. BERGREN, OF SAN FRANCISCO, CALIFORNIA.

SAFETY DELIVERY DOOR.

1,405,661.

Specification of Letters Patent. Patented Feb. 7, 1922.

Application filed November 11, 1919. Serial No. 337,234.

To all whom it may concern:

Be it known that I, LOUIS G. BERGREN, a citizen of the United States, and a resident of the city and county of San Francisco and State of California, have invented a new and useful Safety Delivery Door, of which the following is a specification.

My invention relates to doors for permitting the delivery and collection of 10 articles.

An object of the invention is to provide means applicable to the wall or door of a hotel room, or of a private dwelling for permitting the delivery and collection of 15 articles without leaving them exposed and without disturbing the occupant of the room or dwelling.

My apparatus may be installed in the wall, or the base of a door, so that access may 20 be had thereto by one on the outside of the room into which a parcel is to be delivered or from which a parcel is to be collected. In a hotel room for instance the apparatus may be arranged in the wall between the 25 room and the hall, and deliveries of articles made therethrough into the room without disturbing the guest; or the guest may leave a package in the apparatus to be collected from the hall. In a private dwelling 30 the apparatus may be arranged to permit deliveries from the rear porch or sidewalk into the kitchen or pantry. In all of these cases, the articles delivered or left to be collected are fully protected and are 35 unexposed.

In the drawings, Fig. 1 is a front elevation of the device, taken from the inside of the room. The inner housing plate and door are omitted and parts are sectioned 40 better to disclose the structure.

Fig. 2 is a vertical sectional view of the apparatus. The plane of section is indicated by the line 2—2 of Fig. 1.

Figures 3 and 4 are horizontal sectional 45 views of the device. The planes of section are indicated respectively by the lines 3—3 and 4—4 of Figure 1.

My safety, delivery and collecting appliance comprises a frame 2 adapted to be 50 set within an opening of suitable size cut in the wall or door 3. The length and height of the frame may be as desired, but the width of the frame, that is, the distance through it, is approximately equal to that 55 of the door or wall in which the device is to be installed. The frame is divided into

two portions by the partition wall 4 which forms the top of the passage through the frame. The sides of the passage are formed by the lining plates 6 positioned and spaced 60 from the side walls of the frame by the lugs 7. These plates are preferably shaped like a channel iron as shown in Figure 3 and are each secured in place by a single screw 8. The flat bottom lining plate 9 is similarly 65 secured to lugs 11 and is provided on each edge with hinge lugs forming one-half of the hinge 12 upon which the doors 13 and 14 are hung. The hinge lugs formed on the doors are spaced from the lower edge of the 70 door, and the parts are so proportioned and arranged that when either door is opened to horizontal position as shown in Figure 2, the lower edge of the door engages the under side of the bottom lining 75 plate 9, so that further downward movement is prevented. In the closed position of the doors 13 and 14 they lie flush with the housing plates 16 and 17 respectively, which are 80 suitably apertured to receive the doors. The housing plates are secured in position by bolts 18 having plain heads 19 seated flush in the plate 16 on the outside of the room, and which pass through the wall and terminate in nuts 21 on the inside housing 85 plate 17. Since the frame 2 is positioned between the housing plates, it is held in place by them.

Projecting at an angle of about 45 degrees from the lower left corner of the outer door 13 is an arm 22, the end of which is recessed to engage the point of the head 23 of the rod 24 which is slidably and loosely disposed between the lining and the frame in the adjacent lug 7, and pressed downwardly by a spring 26 interposed between the lug and the head of the rod. The tension of the spring is sufficient to raise the door from the horizontal open position to the closed position and the arm 22, rod and 90 spring structure comprise means for closing the outer door and normally keeping it closed.

Means are provided for locking the outer door when the inner door is open. An apertured lip 27 is provided on the outer door adapted to be engaged by the bolt 28 slidably arranged in the partition wall 4. A lever arm 29 is pivoted on lugs 31 formed on the upper wall of the frame, one end being bifurcated to engage around the stem of the bolt 105 below the head 32. A compression spring 33

is interposed between the lever and the lower end of the bolt, so that normally the end of the lever 29 lies close to the head 32. The other end of the lever is bifurcated and pivotally connected with the upper end of the rod or link 36, the lower end of the link being pivotally connected to the arm 37 projecting at about 45 degrees from the lower end of the inner door 14. This rod too, is disposed between the lining on that side of the frame and passes loosely through an aperture 38 formed in the partition wall 4. The rod is provided with a collar 39 and a spring 41 is interposed between the collar and the partition wall. The spring is resilient enough to close the open door 14, thus serving the same purpose as does spring 26 for door 13. With both doors 13 and 14 closed the bolt 28 is raised and one wishing to make a delivery through the apparatus, pulls open the outer door by means of the recessed finger-hold 42 and thrusts the package through, the inner door swinging down to receive it and serving as a shelf on which the package rests. Release of the outer door permits it to close under the action of the spring 26, and the spring bolt 28 being then in the lower position, snaps into the lip 27 and locks the outer door to the closed position so that it cannot again be opened until the package is removed from the inner door and it is closed, bolt 28 then being lifted free from engagement with the lip 27.

Means are provided for retaining the bolt 28 in the upper position when the inner door is open, so that a package may be left thereon to be collected by one from the outside. A shaft 43 is rotatably mounted at one end in a lug 44 fixed on the partition wall 4, and at the other end in the plate 17, and is provided with a knurled knob 46, on the outside of the housing whereby the shaft may be turned in either direction. A projection 47 on one side of the shaft, adapted to strike the surface of the partition wall 4, limits the turning movement of the shaft to about 180 degrees. This projection or stop is disposed close to the inside surface of the housing plate and together with the knob 46 on the opposite side of the housing plate prevents longitudinal movement of the shaft. The opposite end of the shaft is provided with a pin 48 offset from the axis of the shaft and underlying a flange or lip 49 fixed on the bolt 28. With the stop 47 in contact on one side with the partition wall, the pin 48 is at the lowest point and interferes in no way with the movement of the bolt. When the knob 46 is turned to rotate the shaft through one-half a turn, the offset pin 48 rises, and if the bolt is in the lower or locking position, engages the lip 49 and carries the bolt upwardly to free or unlatch the door 13. If the bolt is in its upper

position when the shaft is turned, the pin in its upper position where it is on a dead center, acts as a stop to prevent the lowering of the bolt into locking position, when the inner door 14 is opened. Thus the knob 46 may be turned to render the bolt 28 inoperative either before or after the inner door has been lowered to receive the package thereon.

The knob and adjacent portions of the housing plate may bear suitable indicia to acquaint the user with the function or operation of the knob.

I claim:

1. A device of the character described comprising a frame, a door arranged on one side of said frame, a spring-pressed bolt for locking said door, a second door pivoted on a horizontal axis on the opposite side of said frame, means for halting the movement of said second door at its horizontal position, a lever on which said bolt is mounted, a link connecting said lever and said second door, and a spring arranged to automatically close said door.

2. A device of the character described comprising a frame having a passage therethrough, doors on said frame for closing said passage, a lever pivoted on said frame, a spring-pressed bolt for locking one of said doors mounted on said lever, and a link connecting said lever with the other door whereby movement of said other door to closed and open position moves said bolt to inoperative and operative position respectively.

3. A device of the character described comprising a frame having a passage therethrough, doors on said frame for closing said passage, a lever pivoted on said frame, a spring-pressed bolt for locking one of said doors mounted on said lever, a link connecting said lever with the other door whereby movement of said other door to closed and open position moves said bolt to inoperative and operative position respectively, and manually operated means for retaining said bolt in and moving it to inoperative position.

4. In a device of the character described, a frame having a passage therethrough, an inner and an outer door on said frame for closing said passage, a lever pivoted on said frame, a spring-pressed bolt for locking said outer door mounted on said lever, a link connecting said lever to said inner door, a shaft journaled adjacent said bolt, a pin on said shaft adapted to engage said bolt, means for limiting the turning movement of said shaft, and means for manually turning said shaft.

In testimony whereof, I have hereunto set my hand at San Francisco, California, this 29th day of October, 1919.

LOUIS G. BERGREN.

In presence of—
C. S. EVANS.
